UNITED STATES PATENT OFFICE

170,639

POURING CAN

Edward J. Hoffman, Jr., Hathorne, Mass.

Application July 29, 1952, Serial No. 20,806

Term of patent 3½ years

(Cl. D58—17)

To all whom it may concern:

Be it known that I, Edward J. Hoffman, Jr., a citizen of the United States, residing at Hathorne, county of Essex, and State of Massachusetts, have invented a new, original, and ornamental Design for a Pouring Can, of which the following is a specification, reference being had to the accompanying drawing, forming part thereof.

Figure 1 is a side elevational view of a pouring can showing my new design;

Figure 2 is a front elevational view thereof, and

Figure 3 is a top plan view.

I claim:

The ornamental design for a pouring can, as shown.

EDWARD J. HOFFMAN, JR.
